HEAT EXCHANGER WITH VARIABLE
CONFIGURATIONJohn E. Ahern, Granada Hills, Calif., assignor to The
Marquardt Corporation, Van Nuys, Calif., a corpora-
tion of CaliforniaFiled Mar. 20, 1961, Ser. No. 97,875
3 Claims. (Cl. 165—101)

This invention relates to a heat exchanger with variable configuration, and more particularly to a heat exchanger operable over a wide range of conditions under which inlet temperature and inlet pressure of a fluid to be cooled increase by a considerable amount.

A heat exchanger for cooling a fluid having a relatively low inlet pressure and temperature should preferably have a large face area and a short flow depth for the fluid. However, when the inlet fluid temperature increases, a small face area and a long flow depth is more efficient. Of course, a long flow depth results in a considerably higher pressure loss through the heat exchanger and the higher pressure loss must be permissible because of an increase in inlet pressure. It has been proposed to supply an aircraft with liquid hydrogen as a source of fuel and to utilize the hydrogen to continually liquefy ambient air obtained from a scoop to provide an oxidant for the hydrogen. The ambient air entering such a cooling system would have a low inlet temperature and pressure at approximately sea level operation of the aircraft but at high altitudes and high flight speeds, high inlet temperature and pressure conditions would prevail. Thus, the heat exchanger arrangement which would be optimum for sea level flight conditions would not be the most suitable for the high altitude flight where a much larger air pressure loss is permissible and the air must be reduced in temperature by a substantially greater degree.

The heat exchanger of the present invention makes use of a baffling system for varying the configuration of the heat exchanger so that it presents a large face area to the air flow and a short air flow depth at sea level operation. At high altitude operation, the baffles are moved into a position wherein a small face area and a long air flow depth is provided. Thus, for a fixed arrangement of heat exchanger tubing, the heat exchanger can operate over a wide range of conditions with increased performance efficiency. When the baffles for the heat exchanger are positioned to present a small face area, the length of flow through the heat exchanger will be substantially greater and a lower refrigerant flow will provide the same air-side performance as when the maximum face area configuration is used.

In the invention, the air is obtained from a scoop located exteriorly of a fuselage, and a pair of baffles can be moved to cause the air to flow serially over three separate sections of the heat exchanger under high altitude flight conditions. For sea level operation, the three sections present one large face area of less depth since the baffles do not divide the air flow. When higher inlet temperatures and pressure are encountered, the large side face area is closed off and air is introduced to the end of the heat exchanger to provide a substantially longer flow depth through the heat exchanger for the air. With the greater flow depth, the velocity of air through the exchanger will be sufficiently higher because of the higher in-

2

let pressure, and this will result in increasing the airside heat transfer coefficient and the performance efficiency of the heat exchanger. Also, lower coolant flows can be utilized because of this high airside efficiency. For maximum performance, cross counter flow of the fluids is maintained by the use of suitable valving.

It is therefore an object of the present invention to provide a heat exchanger of variable configuration in which optimum performance is available under conditions of low available pressure loss and inlet temperature and at conditions of high available pressure loss accompanied with high inlet temperature.

Another object of the present invention is to provide a heat exchanger in which the configuration can be changed by movable baffling to provide a large face area and short flow depth or a small face area and long flow depth.

Another object of the invention is to provide a heat exchanger in which the air flow path through the heat exchanger can be varied in accordance with inlet temperature and available pressure loss and in which the valving of the heat exchanger can provide for cross counter flow of the two fluids regardless of the air flow path.

A further object of the invention is to provide a heat exchanger with variable configuration which is suitable for liquefying air obtained from the atmosphere during flight with a low temperature liquid fuel, such as hydrogen, and which has optimum performance over a large range of flight conditions.

These and other objects of the invention not specifically set forth above will become readily apparent from accompanying description and drawings in which:

FIGURE 1 is a perspective view of the first form of the invention showing the baffles for changing the heat exchanger configuration.

FIGURES 1a and 1b show the position of the valves for the configuration of FIGURE 1.

FIGURE 2 is a vertical section along line 2—2 of FIGURE 1 showing the three sections of the heat exchanger and the baffles in position to provide a large face area and short flow depth for the air.

FIGURE 3 is a partial view of the manifold of the heat exchanger of FIGURE 1 showing the direction of coolant flow when the baffles are moved to provide a small face area and a long flow depth.

FIGURES 3a and 3b show the position of the valves for the configuration of FIGURE 3.

FIGURE 4 is a vertical section similar to FIGURE 2 showing the position of the baffles for a small face area and a long flow depth.

FIGURE 5 is a section along line 5—5 of FIGURE 2 showing the construction of one of the baffles.

FIGURE 6 is an enlarged sectional view, partly in elevation, of one of the valves for controlling the coolant flow to the various sections of the heat exchanger.

FIGURE 7 is a sectional view along line 7—7 of FIGURE 6 showing the passages of the inlet coolant valve during normal sea level operation.

FIGURE 7a is a sectional view similar to FIGURE 7 showing the passages of the outlet coolant valve during normal sea level operation.

FIGURE 8 is a sectional view along line 8—8 of FIGURE 6 showing the paths through the inlet coolant valve during high speed, high altitude operation.

FIGURE 8a is a sectional view similar to FIGURE 8 showing the paths through the outlet coolant valve during high speed, high altitude operation.

Referring to the form of the invention illustrated in FIGURE 1, a passage 20 has an inlet 21 for receiving the fluid to be cooled, such as ambient air. The inlet 21 can be in the form of an air scoop located exteriorly of an aircraft fuselage and the passage portion 22 is contained within the fuselage. Passage 20 contains an enlarged bend portion 23 across which extends heat exchanger 24, and air discharged from the heat exchanger is directed by passage portion 22 to the outlet end 25. In the event that the air or other fluid discharged from heat exchanger 24 is to be liquefied, the outlet end 25 will connect with additional heat exchangers (not shown) for this purpose.

The heat exchanger 24 is comprised of three separate sections 27, 28 and 29 and each of the sections has four separate passes 30, 31, 32 and 33 across the enlarged passage portion 23. Upper manifolds 34, 35 and 36 connect with the end of passes 30 of each of the sections 27, 28 and 29, respectively, and lower manifolds 37, 38 and 39 connect with the end of the passes 33 for each of the sections 27, 28 and 29, respectively. The tubes of the multiple passes of each section are in series and the passes are connected together at the ends of the heat exchanger by bent sections 40, such as illustrated for connecting the passes 31 and 32 of all the sections. The inlet passage 45 which conducts the coolant, such as liquid hydrogen, to the heat exchanger divides into passages 46, 47 and 48 which connect, respectively, with the upper manifolds 34, 35 and 36 of the heat exchanger section. A valve 49 connects the passage 45 with the various branch passages 46, 47 and 48 and this valve determines the direction of flow into the various branch passes. In a similar manner, the outlet passage 50 is connected at valve 51 with branch passages 52, 53 and 54 which communicate with lower manifolds 37, 38 and 39, respectively. The setting of the valve 51 determines the direction of flow in the various branch passages 52, 53 and 54.

When the air flow is unobstructed through the turn portion 23 of passage 20, the heat exchanger sections present a large face area and a short flow depth for the air and this corresponds to optimum operating condition at sea level in which the inlet temperature is relatively low and the permissible pressure drop across the heat exchanger is relatively low. The configuration of the heat exchanger 24 for use at high flight speeds and high altitudes can be changed from the unobstructed configuration to provide a long flow depth and a small face area. Each side of the turn portion 23 of the passage 20 is equipped with a channel track 56 which extends along the inlet portion and curves upwardly to terminate at the location between the sections 27 and 28 of the heat exchanger. A flexible baffle 57 is supported between the channels 56 by a plurality of rods 59 having rollers 58 at opposite ends which are guided by the channels. The baffles can be made of corrugated sheet material in order to conform to the changing shape of the channels 56 and the rods 59 extend between spaced corrugations (see FIGURE 5). A linear actuator 60 of any well known suitable construction can be connected by a link 61 with the baffle 57 in order to move the same along the channel tracks 56.

A second set of channel tracks 62 are located downstream of the heat exchanger 24 on opposite sides of the duct 20. The forward portions of these tracks commence at the outer side of section 27 and curve along the upper surface of turn portion 23. The aft portions of the tracks 62 curve across the duct 20 and terminate at a location between the heat exchanger sections 28 and 29. A flexible baffle 63, similar in construction to baffle 57, is movable along the tracks 62 on rollers 64 connected to the end of shafts extending through the corrugation. A linear actuator 65 can be located at the end of one of the channel tracks 62 and is connected with the baffle 63

5 by a flexible link 66 in order to move the baffle along the tracks. The presence of the movable baffles 57 and 63 make it possible to vary the configuration of the heat exchanger 24 to permit air entering the passage 20 to pass through all the heat exchanger sections simultaneously to provide a large face area and a short air flow depth or to pass through the sections one after another to provide a small face area and a long air flow depth.

10 In FIGURE 2, the baffle 57 is located along the bottom of the duct and the baffle 63 is located along the top surface of the turn portion 23 so that neither baffle interferes with the flow of the air through the passage 20. Thus, the air flows through the sections 27, 28, and 29 of the heat exchanger simultaneously, and the heat exchanger provides a large face area and a short flow depth. In FIGURE 4, the baffle 57 has been moved to extend between the bottom of the passage 20 and the junction between sections 27 and 28 so that the baffle 57 extends completely across the passage. Also, the baffle 63 has been moved to extend between upper surface of passage 20 and the junction between heat exchanger sections 28 and 29. Thus, all of the air entering the passage 20 is diverted by baffle 57 through the heat exchanger 27 and is then diverted by baffle 63 through the section 28 and finally, all the air flows through the heat exchanger section 29. Therefore, the heat exchanger 24 presents to the air a small face area, namely that of an individual section, and a long flow depth, namely the combined flow depth of all three heat exchanger sections.

15 It is understood that the position of the baffles 57 and 63 in FIGURE 2 will be utilized when both the inlet temperature and pressure are relatively low so that sufficient cooling can take place through the flow depth of one section and the pressure drop through this one depth is compatible with the low inlet pressure. When the inlet temperature and pressure greatly increases the baffles 57 and 63 are moved to the positions of FIGURE 4 so that the air in serially transversing the three heat exchanger sections can still be reduced to the desired outlet temperature. The passage of the air through these three sections results in a substantially increased pressure loss but this pressure can be accepted because of the increased inlet pressure available. As previously discussed, the configurations of FIGURES 2 and 4 are suitable for use in an engine which liquefies ambient air with a low temperature supply of fuel, such as hydrogen. The configuration of FIGURE 2 is particularly suitable to sea level static operation while the configuration of FIGURE 4 is particularly suitable to high altitude high speed flight conditions.

20 In order to obtain maximum performance from both configurations of the heat exchanger, a cross counter flow arrangement of the fluids for both configurations is provided and this is accomplished by the valve structures of valves 49 and 51. Referring to FIGURE 6, the structure of valve 49 is illustrated and it is understood that the valve 51 has an identical structure. The valve 49 comprises a casing 70 containing a valve plug 71. The passages 45, 46, 47, and 48 terminate at openings spaced 25 90 degrees around the casing 70. At one cross section, illustrated in FIGURE 7, the plug 71 contains four cross passages 72, 73, 74, and 75 which connect the passages 45-48 with one another at a central terminal 76 when the valve 71 is positioned to the left. Similarly, when the valve plug 71' of valve 51 is positioned to the left, cross passages 72', 73', 74', and 75' connect the passages 50, 52, 53, and 54 with one another at the central terminal 76'.

25 When the valve plugs 71 and 71' of valve 49 and 51, respectively, are moved to the right in FIGURE 6, the section illustrated in FIGURES 8 and 8a align with the external ports. In FIGURE 8, plug 71 of valve 49 contains two passages 80 and 81 which are separate from one another, and passage 80 connects the passages 45 and 48 while the passage 81 connects passages 46 and 47.

In FIGURE 8a, the plug 71' of valve 51 contains passages 80' and 81' and passage 80' connects between passages 50 and 52 while passage 81' connects between the passages 53 and 54. The plugs 71 and 71' for the valves 49 and 51, respectively, are each connected by a shaft 83 to a linear actuator 84 which serves to move the valve plugs between the positions shown in FIGURES 7 and 8. A bellows 85 prevents leakage from the casing 70 and a pressure equalizing vent 86 prevents trapped fluid from interfering with the movement of the plugs. Any suitable signal can be introduced to the actuator 84 through lines 87 to move the valve plugs 71 and 71' into one of their two operating positions.

In the operation of the heat exchanger with the baffles in the position of FIGURE 2, the plugs 71 and 71' of the valves 49 and 50 are in the position shown in the FIGURES 7 and 7a, respectively, to provide for cross counter flow through the sections of the heat exchanger 24. The low temperature coolant is introduced through passage 45 equally to all of the passages 46, 47, and 48 through the passages 72-75 in the valve plugs 71. Manifolds 34, 35, and 36 introduce the coolant to the first passes 30 of the heat exchanger sections 27, 28 and 29, respectively. The coolant flows serially through passes 30, 31, 32, and 33 of each of the heat exchanger sections and the manifolds 37, 38, and 39 receive the discharge coolant. Passages 52, 53, and 54 direct the discharged coolant through passages 73', 74', and 75 of valve 51 to the outlet passage 50.

When liquid hydrogen or other fuel is utilized as the coolant, the outlet passage 50 can lead directly to a propulsion means for an aircraft in which the hydrogen can be combusted with an oxidant to produce thrust. Since the coolant flows in a cross counter flow relationship with the incoming air with the valve arrangement of FIGURES 7 and 7a, an efficient heat transfer relationship exists wherein the warmest air encounters one side of the heat exchanger and the coldest coolant enters the other side. Thus, at sea level flight conditions, a large face area and a short air flow depth can be accompanied by cross counter flow of coolant.

In the operation of the heat exchanger with the baffles in the position of FIGURE 4, plugs 71 and 71' of the valves 49 and 50 are in the position shown in FIGURES 8 and 8a, respectively, to provide for cross counter flow through the sections of the heat exchanger. The low temperature coolant is introduced through passage 45 and all of the coolant is directed through valve passage 80 and passage 48 to the manifold 36 of section 29. As the coolant flows serially through the passes 30-33 of the section 29, it will be flowing in cross counter flow relationship with the air entering this section and flowing in the direction of arrow 90 (see FIGURE 4). The coolant discharged from the section 29 is directed by passage 54 and valve passage 81' to the passage 53 entering the manifold 38 for the heat exchanger section 28. A coolant then flows through the four passes of heat exchanger 28 and is discharged at manifold 35, which is connected by passage 47 with passage 46 through valve passage 81 of valve 49. Since all the air is flowing in the direction of arrow 91 (see FIGURE 4) over the heat exchanger section 28 and since the coldest coolant enters the rear manifold 38, the cross counter flow relationship is maintained in the section 28. All of the coolant is then directed by passage 46 through the manifold 34 to heat exchanger section 27. The coolant flowing through the four passes of section 27 is discharged at the manifold 37 and then is conducted through passage 52 and valve passage 80' of valve 51 to the outlet passage 50. The direction of the air flow over the section 27 is illustrated by arrow 92 (see FIGURE 4) so that it is apparent that the cross counter flow of the coolant is still maintained since the coldest fluid enters the manifold 34.

It is understood that suitable control means can be utilized to correlate the positions of the valve plugs 71 and 71' of the valves 49 and 51 with the positions of the

baffles 57 and 63. When the baffles are moved into the airstream, as illustrated in FIGURE 4, to provide a small face area and a long air flow depth, the plugs 71 and 71' are moved to the right in FIGURE 6 to provide the flow paths shown in FIGURES 8 and 8a. On the other hand, when the baffles are in their stored position, as illustrated in FIGURE 2, the actuator 84 will maintain the plug 71 and 71' in the position corresponding to FIGURES 7 and 7a so that cross counter flow will be maintained with a large face area and a short flow depth. The number of passes of each of the heat exchanger sections can be varied in accordance with any desired operational characteristics and also the numbers of sections which make up the heat exchanger can be varied in conformance with any desired characteristics. It is understood that because of the higher pressure drop across the configuration of FIGURE 4, the small face area of this configuration can provide the same mass flow as the large face area of FIGURE 2 which operates under a smaller pressure differential. Also, since the temperature entering the configuration of FIGURE 2 is lower than that entering the configuration of FIGURE 4, the greater amount of cooling in FIGURE 4 can provide a discharge temperature substantially the same as that leaving the configuration of FIGURE 2.

It is apparent that various other types of heat exchanger arrangements can be utilized where the heat exchanger is divided into sections and baffling is used to conduct the air in sequence to heat exchanger sections when a long air depth flow path is required. Any suitable valving for the cooling and various actuators for the shutters and baffles can be used. Various other modifications are contemplated by those skilled in the art without departing from the spirit and scope of the invention as hereinafter defined by the appended claims.

What is claimed is:

1. A heat transfer device having a configuration variable with operating conditions comprising heat exchanger means located transversely within a duct through which flows a fluid to be cooled, said heat exchanger means comprising a plurality of heat exchanger sections located side by side in a plane transversely across said duct, a first movable baffle located within said duct upstream of said heat exchanger means and located along the surface of the duct to provide a configuration of large face area and short flow depth, a second movable baffle located within said duct downstream of said heat exchanger means and located along the surface of the duct to provide a configuration of large face area and short flow depth, said first and second baffles permitting all of the fluid in said duct to pass through the full face area of said heat exchanger means when in position along the surface of said duct, means for moving said first and second baffles inwardly from the duct surface to reverse the flow of air through adjacent sections and pass all the fluid flow serially through each section to provide a configuration of small face area and long flow depth, inlet and discharge passages for a coolant utilized in said heat exchanger means, and valve means in said inlet and discharge passages for regulating the flow of coolant to said sections to maintain cross counter flow of the coolant for both configurations, said heat exchanger means comprising three sections, said valve means in said inlet passage distributing the coolant equally to said three sections on the downstream side and said valve means in said discharge passage discharging the coolant equally from the upstream side of the heat exchanger sections when both said first and second baffles are in position along the surface of said duct to provide a large face area and a small flow depth, said valve means in said inlet and discharge passage introducing fluid to the first section on the downstream, then to the second section on the upstream and finally to the third section on the downstream side to maintain cross counter flow when the first and second baffles are in their inward positions to provide a small face area and a long flow

depth, each of said valve means comprising a valve plug slidable in a valve housing connected with passages leading to the heat exchanger sections, each of said valve plugs containing two separate sets of valve passages, the first set of valve passages in each plug being operative simultaneously for one configuration of said heat exchanger means and the second set being operative simultaneously for the other configuration of said heat exchanger means.

2. A heat transfer device as defined in claim 1 having actuator means for moving the first and second baffles and having valve actuator means for moving said valve plugs upon change in configuration of said baffles.

3. A heat transfer device as defined in claim 2 wherein said second baffle in its inwardly extending position ex-

5 tends between the upper surface and the junction between said second and third sections.
